IRONING MACHINE

Edward B. Carson, Fort Myers, Fla.

Application June 17, 1938, Serial No. 214,289

5 Claims. (Cl. 38—61)

This invention relates to ironing machine, and has to do with ironing machines intended more particularly for domestic use.

In ironing articles by hand, it is customary to move the iron over the articles in first one direction and then another, such directions being in general substantially perpendicular to one another. This has the effect of smoothing out the articles and preventing wrinkles or creases therein. Further, the changes in direction of movement of the iron, in contact with the article, subjects the threads of the fabric to substantially the same pressure and tension both lengthwise and transversely of the article, avoiding any distortion thereof and imparting thereto a desirable smoothness and sheen. Hand ironing thus produces a noticeably better finish to the article than it is possible to accomplish by machine ironing, as usually practiced, but is open to the objection that it involves more time and labor than ironing by machine.

My invention is directed primarily to the provision of an ironing machine which, in operation, closely approximates hand ironing and imitates to the articles that smoothness and sheen characteristic of articles ironed by hand. More specifically, I provide an ironing machine having two cooperating ironing elements, one of which is a roll driven by a motor, the roll having associated therewith means for reciprocating it lengthwise during rotation of the roll. Further objects and advantages will appear from the detail description.

In the drawings:

Figure 1 is a front view of an ironing machine, partly broken away, embodying my invention and showing the roll at the limit of its lengthwise travel in one direction;

Figure 2 is a sectional view, on an enlarged scale, taken substantially on line 2—2 of Figure 1, certain parts being broken away;

Figure 3 is a central vertical sectional view through the roll, certain parts being broken away and shown in section and certain other parts being shown in elevation, the gear housing being shown partly in section and broken away and partly in elevation and the adjacent portion of the bed plate being shown in elevation;

Figure 4 is a sectional view taken substantially on line 4—4 of Figure 3;

Figure 5 is a development of the cam groove of the cam member mounted on the gear housing;

Figure 6 is a central vertical lengthwise sectional view through the roll and associated cam member, certain parts being shown partly broken

away and in section and certain other parts being shown in elevation, illustrating a modified form of my invention; and

Figure 7 is a fragmentary sectional view, on an enlarged scale, taken substantially on line 7—7 of Figure 6.

I have illustrated my invention, by way of example, as embodied in an ironing machine which is, in general, similar to that disclosed in Patent No. 1,867,839, issued July 19, 1932, to Rudolph W. Janda, for Ironing machine. The machine comprises a suitable stand having a top bed plate 9 supported by depending legs 10. A main gear housing 11, closed at its outer end by a removable cover plate 12, is appropriately mounted 15 upon bed plate 9, at one end thereof, and extends downward therethrough.

A worm gear housing 13 (Figure 2) is suitably secured to the main housing 11 and depends therefrom. Housing 13 receives a worm wheel 14 20 keyed upon a shaft 15 mounted in appropriate bearings and extending upward into housing 11. Worm wheel 14 meshes with a worm 16 secured on a shaft 17 suitably mounted in housing 13, shaft 17 being connected by a flexible coupling 25 (not shown), as in the above identified patent, to an electric motor 18 suitably suspended from bed plate 9. A clutch and eccentric assembly 18^a is associated with shaft 15 in the same manner as in the patent referred to, and is connected by 30 an arm 19 and a universal connection 20, to the lower end of an arm 21 secured upon the outer end of a shoe operating shaft 22. The latter shaft extends from gear housing 11 inward over the bed plate 9, through a tubular boss 23 extending 35 from housing 11, a sleeve 24 secured at one end in boss 23 and a bracket 25, receiving the other end of sleeve 24 and appropriately secured to bed plate 9. Shaft 24 projects beyond bracket 25 and carries shoe supporting and receiving means 26, 40 comprising an arm 27 upon which is mounted a shoe 28. Operation of the shoe shaft 22 is controlled by a trip member 29 normally held in operative position, by a rod 30 yieldingly held in raised position, by a coil compression spring 31 45 disposed about the rod and confined between an abutment member 32 secured upon the rod, and the lower wall of a recess 33 formed in housing 11 and receiving the spring and the upper portion of the rod. A button 34 is secured upon the 50 upper end of the rod for convenience in depressing the latter. The shoe shaft operating means, the control means therefor and the shoe supporting and releasing means are all fully disclosed in the above identified patent to Rudolph 55

W. Janda and need not be shown nor described here in greater detail. Suffice it to state that shaft 15 is driven from the motor and suitable control means is provided for effecting movement 5 of the shoe as desired.

Shaft 15 is disposed coaxially with an upper shaft section 15^a and has secured thereon, above the assembly 18^a, a clutch member 35. Shaft section 15^a is rotatably mounted through a thickened 10 element or rib 36 of housing 11 and has appropriately mounted thereon, for sliding movement, a clutch member 37 which cooperates with clutch member 35. An arm 38 is loosely mounted on shoe shaft 22 and has lost motion connection 15 to arm 21. At its forward end arm 38 is appropriately connected to clutch member 37 for raising and lowering the latter, in accordance with rearward and forward movements of shoe 28. A control plate 40 is slidably mounted on 20 rib 36, by pin and slot means 41, this plate being provided with a suitably formed opening 42 receiving a pin 43 connected to the forward end of arm 38. Plate 40 is adjusted by means of a rod 44 connected thereto and slidable through the 25 front wall of housing 11, the forward end of this rod having a suitably shaped head or button 45 approximately secured thereon. In the normal position of plate 40, shown in Figure 2, clutch member 37 is moved into and out of operative 30 position, in accordance with the movements of the shoe shaft 22. By moving plate 40 into its outer or forward position, clutch member 37 is held in its raised or inoperative position, when the shoe 28 is moved to its forward position. The 35 construction and operation of the parts just referred to are fully disclosed in the patent to Rudolph W. Janda, above identified, and need not be further illustrated nor described here.

A bevel pinion 47 is secured upon the upper 40 end of shaft section 15^a, above rib 36, and meshes with a bevel gear 48 secured upon the outer end of a roll shaft 49. The latter shaft is rotatably mounted through a boss 50 projecting inward of gear housing 11, from the inner end wall of the 45 latter. A boss 51 projects from the outer face of the inner end wall of housing 11 and has extending therefrom an integral tubular hub 52, this hub and boss 51 receiving the inner end portion of a tubular member or sleeve 53, secured 50 in hub 52 and boss 51 in any appropriate manner.

Shaft 49 extends outwardly beyond the other 55 end of sleeve 53, the latter being provided at said other end with a bushing 54 rotatably supporting shaft 49. A washer 55 is disposed about shaft 49 and is confined between the inner end of sleeve 53 and a thrust collar 55^a pinned or otherwise suitably secured to shaft 49. The latter shaft, which is the roll drive shaft, is thus 60 rotatably mounted in the supporting structure, comprising gear housing 11 and sleeve 53, and this shaft is driven by the motor when clutch member 37 is in its lowered or operative position.

65 A roll 56 is mounted concentrically with shaft 49 and sleeve 53 for rotation and for lengthwise reciprocating movement. This roll comprises a sheet metal cylinder 57 provided with a suitable pad 58. A spider 59 is suitably secured, as by riveting, within cylinder 57 a short distance inward beyond thrust collar 55^a. Spider 59 is provided with a hub 60 having a squared bore 61 which slidably receives squared and reduced portion 49^a of shaft 49, projecting beyond thrust collar 55^a. Hub 60 comprises a squared portion 70

60^a appropriately slotted for reception of two pairs of rollers 62 mounted to turn freely upon pins 63 appropriately secured in portion 60^a of hub 60. The rollers of each pair contact the opposite flat faces of squared portion 49^a of shaft 49, as will be clear from Figures 3 and 7. Roll 56 is provided, adjacent its other end, with a spider 64 riveted to cylinder 57, which spider is provided with a hub 65, rotatably and slidably mounted upon sleeve 53 by means of a bushing 10 66. Roll 56 is thus mounted upon sleeve 53 for rotation about the latter and for reciprocation lengthwise thereof.

Spider 64 is provided with an integral finger 15 67, at its periphery, extending lengthwise of cylinder 57 toward the adjacent end thereof. Finger 67 is provided, at its outer end, with a collar 68 projecting inward of roller 56 radially thereof. A headed and shouldered pin 69 is secured in collar 68 and carries, at its inner end, a 20 roller 70. Roller 70 engages within a cam groove 71 of a cam member 72 mounted upon boss 51. Groove 71 is of undulatory formation, as will be clear from Figure 5. Normally, cam member 72 is fixed to boss 51, with roller 70 engaging in groove 71 and cooperating with the walls thereof for reciprocating roll 56 lengthwise, during rotation thereof. The spider 59 and associated rollers 62 cooperate with the squared portion 49^a of roll shaft 49 for rotating the 30 roll 56, while permitting lengthwise movement of the roll and avoiding objectionable friction during such movement. It will also be noted that the means for reciprocating the roll 56 is effective for limiting lengthwise movement thereof 35 relative to shaft 49, preventing withdrawal of the roll from its normal operating relation to shaft 49 and the parts associated therewith.

Cam member 72 is provided, at its outer end, with two integral web elements 73 of segmental 40 shape. These elements define a substantially rectangular slot 74 which receives a rectangular enlargement 52^a of hub 52, at the outer end of the latter. Each web element 73 is provided with a lengthwise slot 75 which receives a flat headed screw 76 threaded into boss 51. Cam member 72 is further provided, at the front thereof, with an outwardly projecting lug 77 which fits into a corresponding notch 78 in boss 51. A screw 79, provided with a socketed head, 50 passes through lug 77 and threads into boss 51, lug 77 being appropriately recessed for reception of the head of screw 79. Web elements 73 fit snugly about enlargement 52^a and cooperate therewith for holding the cam member 72 against 55 turning movement. When screw 79 is turned tightly into boss 51, cam member 72 is locked against movement transversely of hub 52 and effectively anchored to boss 51, the heads of screws 76 bearing against the inner faces of segments 73, as shown in Figure 3.

In order to place the roll 56 upon the machine, screw 79 is threaded out of boss 51 and the cam member is slid toward the front of the machine to the extent limited by enlargement 52^a of hub 65 52, it being noted (Figure 4) that the rearward portion of enlargement 52^a is shaped conformably to the corresponding end of slot 74 and is spaced a considerable distance therefrom. This permits forward movement of cam 72 to such 70 an extent that, when the roll 56 is turned into position such that pin 69 is coaxial with screw 79, pin 69 and roller 70 carried thereby will clear cam member 72, thus permitting the roll 56 to be moved lengthwise away from gear hous- 75

ing 11 and, if desired, completely withdrawn from sleeve 53 and shaft 49. In replacing the roll, it is slid onto shaft 49 and sleeve 53 into position with pin 69 and roller 70 in alignment 5 with cam groove 71 and coaxial with pin 69, cam member 12 being in its extreme forward position. The cam member 12 is then slid rearward into such position that the roller 70 engages in groove 72, in which position it is secured by means of screw 79, as previously described. The roll 56 may thus be removed and replaced with expedition and facility, as conditions may require, the means for reciprocating the roll also serving to retain it in position upon 10 the supporting structure.

In the modified form shown in Figure 6, a cam member 80 fits about an enlargement 52^b at the outer end of hub 52 and is secured to boss 51 by cap screws 81. The cam member 12 of Figure 20 3 is a box cam, whereas the cam member 80 of Figure 6 is an open cam provided at its inner side with an undulatory cam track, as will be clear from Figure 6, and no adjustment thereof is necessary for mounting or demounting of the 25 roll 56. Roll shaft 49 is provided with a squared portion 49^b extending through hub 60 of spider 69, and with a cylindrical threaded portion 49^c extending from squared portion 49^b. A compression coil spring 82 is confined between hub 60 30 of spider 59, about the end portion of shaft 49, and a washer 83 disposed about portion 49^c of shaft 49 and abutting a nut 84 threaded upon the shaft. Spring 82 maintains roller 70 in contact with the undulatory track of cam member 80, which cooperates with roller 70 and associated parts for reciprocating roll 56 lengthwise, during rotation thereof. By removing nut 84 the roll 56 may be removed and replaced with expedition and facility, as required.

40 In both forms of my invention illustrated, the roll of the machine is reciprocated lengthwise during rotation thereof. The extent of reciprocation need not be great, approximately one-quarter of an inch sufficing in most cases. In Figure 45 1 the roll is shown at the limit of its movement toward the right, as indicated by the arrow a₁, in which position the ends of the roll are flush with the ends of the shoe 28. After reaching the position shown in Figure 1 the roll, in its 50 continued rotation, is moved in the opposite direction, indicated by the arrow a₂, so as to extend beyond the left hand end of shoe 28, as viewed in Figure 1, a short distance, approximately one-quarter of an inch. In both forms 55 of my invention illustrated by way of example, the roll is rotated by power derived from the motor 18 and is also reciprocated by power derived from the same source, this motor also furnishing the power for moving the shoe to and from the 60 roll.

While I have illustrated two preferred forms of my invention, by way of example, changes in construction and arrangement thereof may be resorted to without departing from the field and 65 scope of the same, and I intend to include all such variations, as fall within the scope of the appended claims, in this application in which the preferred forms only of my invention have been disclosed.

70 I claim:

1. In an ironing machine, a supporting structure comprising a gear housing and a tubular member projecting from said housing, a roll mounted for rotation about said member and for

lengthwise reciprocation, a motor having driving connection to said roll effective for rotating the latter, a cam engaging member carried by said roll projecting radially thereof and held against relative movement lengthwise of said roll, a cam member normally fixed to said housing and defining an undulatory cam groove receiving said cam engaging member and cooperating therewith for reciprocating said roll during rotation thereof, and means mounting said cam member for adjustment into position to clear said cam engaging member.

2. In an ironing machine, a supporting structure comprising a gear housing and a tubular member projecting from said housing, a roll 15 mounted for rotation about said member and for lengthwise reciprocation, a motor having driving connection to said roll effective for rotating the latter, a cam engaging member carried by said roll within the latter projecting radially inward thereof and held against relative movement lengthwise of said roll, a cam member normally fixed to said housing extending into an end of said roll and defining an undulatory cam groove 20 receiving said cam engaging member and cooperating therewith for reciprocating said roll during rotation thereof, and means mounting said cam member for adjustment into position to clear 25 said cam engaging member.

3. In an ironing machine, a supporting structure comprising a gear housing and a tubular member projecting from said housing, a shaft 30 rotatably mounted through said member and projecting outward beyond the end thereof remote from said housing, a motor having driving connection to said shaft, the outer portion of the latter being squared, a roll rotatably mounted adjacent one end on said tubular member, roller means carried by said roll engaging said squared portion of said shaft and establishing driving 35 connection between the latter and said roll while permitting lengthwise reciprocation of said roll, and means for reciprocating said roll during rotation thereof comprising an annular undulatory cam track adjacent one end of said roll concentric therewith.

4. In an ironing machine, a support, a roll mounted on said support for rotation and lengthwise reciprocation, a cam member carried by said support comprising an annular undulatory 50 cam track adjacent one end of said roll and concentric therewith, a cam engaging member carried by said roll, a motor, driving connections between said motor and said roll effective for rotating the latter, and means supplementary to 55 said driving connections for yieldingly urging said roll lengthwise and holding said cam engaging member in contact with said cam member.

5. In an ironing machine, a supporting structure comprising a gear housing and a tubular member projecting from said housing, a shaft 60 rotatably mounted through said member and projecting outward beyond the end thereof remote from said housing, a motor having driving connection to said shaft, a spider secured in said roll beyond said remote end of said tubular member having a sliding and driving fit with said projecting portion of said shaft, a cam member carried by said housing, a cam engaging member carried by said roll, an abutment member on said shaft outward beyond said spider, and a coil compression spring confined between said abutment member and said spider.

EDWARD B. CARSON.
